Clifford Brooks Stevens, Milwaukee, Wis., assignor to S. C. Johnson & Son, Inc., Racine, Wis.

Application March 6, 1948, Serial No. 144,933

Term of patent 14 years

(Cl. D9—2)

To all whom it may concern:

Be it known that I, Clifford Brooks Stevens, a citizen of the United States, residing at Milwaukee, in the county of Milwaukee and State of Wisconsin, have invented a new, original, and ornamental Design for a Floor Polisher, of which the following is a specification, reference being had to the accompanying drawing, forming part thereof.

Figure 1 is a top plan view of a floor polisher, showing my new design.

Figure 2 is a side elevational view of Figure 1.

Figure 3 is a front elevational view of Figure 1.

Figure 4 is a perspective view of Figure 1.

I claim:

The ornamental design for a floor polisher, as shown.

CLIFFORD BROOKS STEVENS.
